(57) **CLAIM**

The ornamental design for riding jeans, as shown and described.

DESCRIPTION

FIG. 1 is a front perspective view of my new design for riding jeans;

FIG. 2 is a front view thereof;

FIG. 3 is a rear view thereof;

FIG. 4 is a left side view thereof;

FIG. 5 is a right side view thereof;

FIG. 6 is an inside out view of the front showing an interior layer thereof; and,

FIG. 7 is an inside out view of the rear showing an interior pocket thereof.

The broken lines in the figures illustrate stitching on the riding jeans which forms no part of the claimed design.
